UNITED STATES PATENT OFFICE.

CHARLES E. JONES, OF GREENCASTLE, IOWA, ASSIGNOR OF ONE-HALF OF HIS RIGHT TO GARNER M. TRIPP, OF SAME PLACE.

CHECK-ROW CORN-MARKER.

SPECIFICATION forming part of Letters Patent No. 229,140, dated June 22, 1880.

Application filed February 12, 1880.

To all whom it may concern:

Be it known that I, CHARLES E. JONES, of Greencastle, in the county of Jasper and State of Iowa, have invented certain new and useful 5 Improvements in Check-Row Corn-Markers; and I do hereby declare that the following is a full, clear, and exact description of the invention, which will enable others skilled in the art to which it appertains to make and use the 10 same, reference being had to the accompanying drawings, which form a part of this specification.

Figure 1 is a front view, Fig. 2 is a top plan, and Fig. 3 is a side view, of my improved corn- 15 marker.

Corresponding parts in the several figures are denoted by like letters of reference.

This invention relates to check-row corn-markers; and it consists in certain improvements 20 in the construction of the same, which will be hereinafter more fully described, and particularly pointed out in the claim.

In the drawings hereto annexed, A represents the frame of the marker, which is provided 25 with an axle, B, supported upon the transporting-wheels C C, which carry the machine.

To the front side of frame A, near the tongue T, are pivoted two beams or semi-axes, D D, having at their extreme ends spindles E, upon 30 which the marking-wheels F F are journaled.

Links or bails G G, pivoted to the front side of frame A, near the free ends of the semi-

axles D D, confine the motion of the latter, and prevent them from being thrown out of 35 position.

In operation, the frame of the machine is carried upon the transporting-wheels C C, while the marking-wheels F F, being journaled upon the pivoted stub-axes or semi-axes D D, adapt 40 themselves to any unevenness in the ground.

I am aware that short axles hinged to the ends of a main axle and operated by levers have been used before; also, that a long axle and a short axle, each having wheels, have been 45 connected and operated by levers under the control of the driver to raise either set of wheels at pleasure; and neither of these constructions is claimed herein.

Having thus described my invention, I claim 50 and desire to secure by Letters Patent of the United States—

The combination, with the frame A, supported upon the transporting-wheels C C, of the stub-axes D D, pivoted to the front of said 55 frame and having marking-wheels F F, and the links or bails G G, pivoted to the front of the frame A and confining the stub-axes D D, as set forth.

In testimony that I claim the foregoing as 60 my own I have hereto affixed my signature in presence of two witnesses.

CHARLES E. JONES.
